A. G. RICE

RIVET BREAKER OR CUTTER

Filed Dec. 10, 1919

Patented Jan. 1, 1924.

1,479,320

UNITED STATES PATENT OFFICE.

ALBERT G. RICE, OF INDIANAPOLIS, INDIANA, ASSIGNOR TO RICE MANUFACTURING COMPANY, OF INDIANAPOLIS, INDIANA.

RIVET BREAKER OR CUTTER.

Application filed December 10, 1919. Serial No. 343,893.

To all whom it may concern:

Be it known that I, ALBERT G. RICE, a citizen of the United States, residing at Indianapolis, in the county of Marion and 5 State of Indiana, have invented certain new and useful Improvements in Rivet Breakers or Cutters, of which the following is a specification.

The present invention relates to improvements in that type of apparatus known generally as pneumatic rivet breakers or cutters, the object in view being to provide a practical device of this character possessing the strength, power and durability required 15 for the work performed by this class of machines.

The invention, while constructed along generally well-known lines, possesses characteristics which, being lacking in those at 20 present in use, give rise to simplicity, ease in manipulation, and efficiency in results.

To this end the invention consists of a plunger operable by suitable air pressure to deliver a tremendous blow upon the cutting tool head or a very light blow according 25 to the desire of the operator and by virtue of my particular form of valve which insures the full benefit of the pressure head, the plunger resuming its initial driving 30 position without shock or "back kick" under the control of a regulatable by-pass.

In carrying out the invention, I also provide shock absorbing means for taking up the impact of the plunger in its movements 35 to and fro.

With these ends in view the invention consists in the novel combination and arrangement of parts as will be hereinafter fully described and claimed.

40 For a full understanding of the invention, reference is to be had to the following description and accompanying drawings, in which:—

Figure 1 is a longitudinal sectional view 45 of an apparatus constructed in accordance with my invention.

Figure 2 is an enlarged sectional view of the head of the rivet breaker.

Figure 3 is an end elevation of the invention.

Figure 4 is an enlarged sectional view showing more clearly the valve passages and the intake and exhaust ports with which they connect; and

55 Figure 5 is a detail view of the valve

showing more clearly the formation of the intake and exhaust passage.

Corresponding and like parts are referred to in the following description and indicated in all the views of the drawings by 60 the same reference characters.

Referring to the drawings and specifically describing the preferred embodiment of my invention, 1 designates an elongated barrel of suitable diameter and length upon the 65 lower end of which is mounted the nose piece 2. The end of the nose piece is inferiorly threaded to receive the bushing 3 which is screwed thereinto and forms the guide holding means for the tool 4 which is 70 employed in this device. At the opposite end of the barrel a head piece 5 is mounted, said head piece having an air port 6 establishing communication between the valve 75 chamber 7 and the interior of the barrel 1 at one end. Within the valve chamber is mounted the air controlling valve 8 revolvable by means of the operating handle 9 so as to bring about the registration of the proper ports in the use of this device. The 80 valve head 5 is provided with an opening at one side to receive the pipe handle 10 for the air line, said handle being provided with a cut-out cock 11. At right angles to this inlet passage for the air pressure is 85 provided an exhaust port 12 into which is screwed the exhaust elbow 13. Directly opposite the exhaust port 12 is a corresponding port 14 threaded to receive the street 90 elbow 15. Directly opposite the inlet 10 the head is also provided with a further port 95 which for the purposes of distinction I term the by-pass exhaust port, indicated at 16, said port being threaded to receive the tubular handle 17.

The valve 8 is retained within the valve chamber by the cap plate 18 suitably to the end of the head by the fastening means 19. At the lower end of the device I provide a passage through the nose piece 2 and the side of the barrel, as indicated at 20, to receive an elbow 21, a by-pass hose or pipe 22 establishing communication between the elbows 15 and 21 above referred to. An important feature of this invention resides in 100 the provision of a by-pass air reducer cock 23 by means of which the by-pass pressure may be readily regulated as will be herein-after more specifically pointed out. Within 105 the barrel 1 is reciprocably mounted the 110

plunger 24, which is adapted to be actuated to and fro by means of compressed air under the control of the air valve 8, this plunger fitting nicely into the bore of the barrel and being susceptible of delivering repeated blows upon the head of the tool 4 which projects into the barrel a suitable distance. Surrounding the inner end or head of the tool is a coil spring 25 which is secured in any desired manner at this point and is designed to receive or take up the impact of the plunger when the head of the tool is materially shifted from its normal position. A corresponding spring 26 is mounted at the head end of the device so as to absorb the shock of the plunger in returning to its initial driving position under the control of the by-pass pressure.

Reverting to the construction of the valve 8, I desire to be understood that one of the main features of this invention which makes it particularly practical is the formation of the main passage 8'. In previous devices of this character the corresponding passage is usually formed by making a bore longitudinally of the valve, and a corresponding bore transversely through the side of the valve to intersect the first bore. This makes a right angle passage through which the air under pressure must pass before admission into the interior of the barrel. The defect of such a passage lies in the fact that the air is more or less retarded owing to a rebound against the wall of the longitudinal bore at the point of intersection of the two bores referred to. I have found by considerable experimentation that this defect or disadvantage may be overcome with considerable increase in efficiency of the device by forming the main passage in the valve as shown in Figure 5 more particularly of the drawings. It will be observed that this passage 8' is formed by cutting through the material of the valve from one side and through the bottom, the inner wall 8" being curved so that the air will pass around the passage with substantially no tendency to retardation into the interior of the barrel at the head end of the same. The wall 8' of the passage where it meets the wall of the port 6 is flush with said wall so that at this side of the passage the least amount of interference is interposed to the movement of the air from the valve into the barrel. In addition to this passage just described the valve is provided with a peripheral passage 8^a formed by routing out a shallow groove extending partially around the side of the valve in such a position as to establish communication between two of the ports in the head 5 in order to permit of admission of pressure into the by-pass and the exhausting of the pressure therethrough.

In the manufacture of this device, it may be added, both the nose piece 2 and the head piece 5 are forced upon the ends of the bar-

rel under the action of very heavy pressure and by a proper fusing of the material these parts are so fixed upon the barrel as to be prevented from becoming loosened due to the use of the device and the vibrations produced by the reciprocation of the plunger. Passing now to the operation of the implement, to best carry out the rivet cutting process the operator takes hold of the left-side handle with his left hand and operates the valve handle 9 with his right hand, while a second man, where the apparatus is of the larger type, takes hold of the right-side and a third man supports the tool and holds it on the rivet to be extracted. The cut-out cock 11 is now opened to admit the air pressure into the head of the cutter device, thus preparing the machine for its operation under the control of the operator in the manipulation of the handle 9. By raising this handle to the dotted line position shown in Figure 3 the passage 8' of the valve establishes communication between the intake 10 and the port 6 entering the barrel at the head end. The full pressure head acts upon the plunger to drive it against the tool head at the opposite end, the handle 9 being quickly returned to its initial full line position shown in Figure 3 whereupon the passage 8' is connected with the exhaust 13. Simultaneous with this movement of the handle last mentioned the by-pass passage 8^a is positioned to admit pressure from the intake into the by-pass 22 which pressure will be effective to quickly return the plunger 24 to the head end of the barrel and the pressure with which this return is secured may be controlled by an adjustment of the by-pass air reducer cock 23. This cut-off may be so adjusted that while the return of the plunger 24 will be very quick, such return may be obtained without perceptible shock to the operators, and this is a very important feature of my invention. The great importance of the by-pass regulating valve 23 will be obvious when it is taken into account that applicant's device will work efficiently on a great range of air pressures. If, therefore, the by-pass valve 23 were omitted and the by-pass 22 provided of suitable bore to return the plunger 24 without shock with 50 pounds pressure in the air line, with 90 pounds pressure in the air line plunger would be returned with considerable shock or back kick tending to quickly tire the operator and lower the efficiency of both the device and the operator. In operating the plunger to again drive it against the tool the passage 8^a just referred to will be so positioned as to open the by-pass port 14 to its exhaust port 16, exhausting the pressure through the handle 17.

It may be further pointed out that whenever the contents of the barrel are required to be displaced it only requires the removal

of the nose bushing 3 which may readily be screwed in and out of said nose piece for this purpose, the passage through the nose piece being of a diameter corresponding to 5 the diameter of the bore of the barrel 1 as will be readily observed by reference to Figure 1.

As heretofore premised, it will be obvious from the foregoing that after a little practice, the operator may so control the air pressure that the plunger will deliver a heavy blow upon the tool as when commencing the cutting action, or so actuate said plunger as to deliver a light blow, all of 15 which is obtained by a proper manipulation of the handle 9 of the air control valve. The particular tool may be displaced and another substituted therefore very readily without the removal of any part for this 20 purpose, and this is a distinct advantage when the tools require sharpening or other treatment.

Having thus described the invention, what I claim as new and desire to secure by 25 Letters Patent, is:—

1. A pneumatic implement of the class involving in operation a manually controlled alternating stroke, comprising an elongated barrel having an inlet provided at one side 30 of the head of the barrel to admit a pressure fluid, a plunger reciprocally mounted therein for actuation by said fluid, a rotatable valve mounted in the head of the barrel communicating with said inlet and hav-

ing an unobstructed curved wall free from 35 shoulders to direct the full pressure at maximum velocity immediately into the barrel against an end of the plunger whereby the direction of movement of the fluid is changed into line with the movement of the 40 plunger with a minimum loss of effective impact force, and means for operating said valve.

2. A pneumatic implement of the class involving in operation a manually controlled 45 alternating stroke, comprising an elongated barrel having an intake provided at one side of the head of the barrel to admit a pressure fluid, a plunger reciprocally mounted therein for actuation by said fluid, a rotatable valve mounted in the head of the barrel 50 communicating with said inlet and having an unobstructed passage formed by cutting out the material of the valve through the bottom and one side and merging the 55 inner walls of the opening thus formed into a curved connecting wall free from shoulders and adapted to direct the full pressure at maximum velocity immediately into the barrel against an end of the plunger, 60 whereby the direction of movement of the fluid is changed into line with the movement of the plunger with a minimum loss of effective force, and means for operating 65 said valve.

In testimony whereof I affix my signature.

ALBERT G. RICE.
